DESIGN FOR A BEVERAGE DISPENSER

Charles William Lloyd, Brooklyn, N. Y., assignor to Dispensers, Inc., Brooklyn, N. Y., a corporation of New York

Application January 17, 1947, Serial No. 136,203

Term of patent 14 years

(Cl. D2—3)

To all whom it may concern:

Be it known that I, Charles William Lloyd, a citizen of the United States of America, residing at Brooklyn, in the county of Kings and State of New York, have invented a new, original, and ornamental Design for a Beverage Dispenser, of which the following is a specification, reference being had to the accompanying drawing, forming part thereof.

In the drawing:

Fig. 1 is a side elevational view of a beverage dispenser, showing my new design;

Fig. 2 is a top plan view thereof; and

Fig. 3 is a fragmentary perspective view of the dispenser shown in Figs. 1 and 2.

I claim:

The ornamental design for a beverage dispenser, substantially as shown.

CHARLES WILLIAM LLOYD.
